UNITED STATES PATENT OFFICE.

HOMER B. RICH, OF ALLSTON, MASSACHUSETTS.

RECEPTACLE.

1,251,921.

Specification of Letters Patent.

Patented Jan. 1, 1918.

Application filed April 5, 1916. Serial No. 88,979.

To all whom it may concern:

Be it known that I, HOMER B. RICH, a citizen of the United States, and resident of Allston, in the county of Suffolk and State of Massachusetts, have invented new and useful Improvements in Receptacles, of which the following is a specification.

This invention relates to a vessel having a pivotal lid, which has been designed particularly for use as a sputum cup and which is preferably constructed of paperoid so that it may be manufactured at small cost and be destroyed after use, although any suitable sheet material, such as ordinary paper of suitable stiffness, metalloid, or even flexible sheet metal may be employed and the vessel may be constructed of any shape and of any size for any desired purpose, such as for use as a drinking cup, lunch box, garbage receptacle, etc.

It has been proposed to construct sputum cups by providing each cup with a tab comprising an extension of a portion of one side of the cup or box, forming a lid or cover with a slot fitting over the tab to constitute a pivot, and holding the lid in place by means of an elastic band passed around the box and through notches in the edges of the cover near the pivotal edge. Such boxes are fairly satisfactory when properly adjusted and intelligently used, but it has been found that when used in hospitals by patients in weakened condition, difficulty is experienced in raising the lid and maintaining it open against the action of the elastic band. Furthermore, there has been a tendency for the lid to slip off of the tab when the device is clumsily used by such persons.

One object of my invention is to overcome the above objections by providing a fastening means on the tab, preferably in the form of a tongue integral with the tab, to prevent the cover from slipping off the tab and at the same time to act as a resilient cover closing device, thus eliminating the necessity for an elastic band. Another object is to construct the vessel of blanks formed from the sheet material in such a way that a minimum number of blanks is required, preferably only two, and to so shape the lid and vessel including the tab and tongue that only a single stamping or cutting operation is required to completely form the blanks for the box and cover, respectively, thus affording an exceedingly economical construction. A further object is to so form

the pivotal connection that the lid will at all times be pressed in the direction of its closed position by the pivotal connection, thus automatically closing the vessel and also holding the lid more tightly against the vessel when in closed position.

In the accompanying drawings which illustrate one embodiment of my invention,

Figure 1 is a longitudinal sectional view;

Fig. 2 is a front elevation;

Fig. 3 is a detail sectional view showing the lid in elevated position; and

Fig. 4 is a detail sectional view of a modified form of the invention.

In the embodiment of my invention illustrated in Figs. 1 to 3, the box B, which may be of any ordinary form except as herein-after set forth, is provided at one side with one or more tabs B', preferably by leaving one or more extensions of suitable length and breadth on the side of the box when stamping the blank therefor. By the same stamping operation a U-shaped tongue B² may be conveniently cut in each tab B'.

The lid C may be of the same material as the box, although I prefer to construct it of stiffer material when employing paperoid, and a slot C' of suitable length and breadth to receive the tab B' is provided transversely of the lid. After the lid is placed in position with the tab projecting through the slot, the tongue B² is sprung into the position shown in Fig. 1.

When the lid is raised the tab B' flexes backwardly as shown in Fig. 3, and the portion of the lid extending over the pivotal edge of the vessel engages the side of the vessel thus preventing the lid from being rotated through more than approximately ninety degrees. The tab B' has sufficient resiliency to close the lid even when the latter is opened slightly beyond its vertical position and also to press the lid against the top of the vessel when closed, thus affording an automatic and tight closure.

In the modified form of my invention shown in Fig. 4, the slot is cut in the extension B³ of one side of the box, and the tab fitting through the slot comprises extension C² of the lid C having a tongue C³ on the lower side thereof. The extension B³ of the box B may or may not extend the full width of the box. The tongue C³ serves to automatically close the lid and to press the lid against the top of the vessel when closed.

Instead of employing only a single tab and a single slot the pivotal connection may obviously consist of two or more tabs and slots.

What I claim is:

1. A vessel, a lid therefor, the lid having a transverse slot therein, and a member on said vessel projecting through said slot, and yielding means at the pivotal connection for retaining the lid on the vessel and for yieldingly urging the lid toward the closed position.
2. A vessel, a lid therefor, and a pivotal connection between said vessel and said lid comprising a slot in said lid and a tab on said vessel projecting through said slot, and yielding means on the tab for retaining the lid thereon.
3. A sheet-material vessel having an integral tab on one side thereof, a lid having a slot fitting over said tab, and a struck-up tongue on said tab for pivotally retaining said lid thereon.
4. A pivotal connection between two members comprising a slot in one member and a tab on the other member fitting through said slot and having a flexible tongue thereon for maintaining said tab within said slot.
5. A pivotal connection between two members comprising a slot in one member, and

an elastic means disposed on one of said members in operative relation to the other of said members so as yieldingly to urge the members toward each other.

6. A pivotal connection between two members comprising a slot in a portion of one member, a portion of the other member being shaped to project through the slot, and elastic means disposed on one of said portions in operative relation to the other of said portions so as yieldingly to urge the members toward each other.

7. A pivotal connection between two members comprising a slot in one member and a tab on the other member fitting through the slot, and a flexible tongue disposed on one of said members so as to engage the other of said members and yieldingly urge the members toward each other.

8. A pivotal connection between two members comprising a slot in a portion of one member, a portion of the other member being shaped to project through the slot, and a flexible tongue disposed on one of said portions so as to engage the other of said portions and yieldingly urge the members toward each other.

Signed by me at Boston, Massachusetts, this 29th day of March, 1916.

HOMER B. RICH.
